FLUID PRESSURE OPERATED FLOW
CONTROL VALVE

William B. Bolger, Cleveland, Ohio

Application May 20, 1947, Serial No. 749,314

4 Claims. (Cl. 137—657)

1

This invention relates to a flow control valve and is shown and described as applied to a waste disposal unit for railway cars and the like employing an automatic control combination by which the unit is caused to discharge its contents automatically at preselected speeds of the vehicle.

In railway sleeping cars, particularly those of the "roomette" type, the problem of disposing of the waste from the washrooms and toilet facilities has presented a number of difficulties due to the frequent entrance of the trains into the station areas. Usually, for such cars, removable tanks are connected to the washroom and toilet facilities for accumulating wastes therefrom while the cars are in the station, and must be removed by attendants in the station before the car resumes travel. In the case of day coaches and the like, the washrooms and toilets generally are locked while the train is standing in a station and during its entry into and departure from a station area.

For the purposes of illustration, the valve is shown in connection with a small and compact normally sealed waste disposal unit, for the washroom and toilet facilities of railway cars, which opens automatically and discharges its contents consequent upon the vehicle reaching a predetermined relatively high speed which is normally attained by the train when it has reached the open country.

The valve is arranged to be operated from the usual compressed air lines normally provided on railway cars and to be controlled by a simple automatic control mechanism which may be set to cause operation of the unit at a number of different preselected speeds of the car.

The principal object of the present invention is to provide a valve which is non-clogging and is operated by fluid pressure.

Other objects and advantages will become apparent from the following description wherein reference is made to the drawings in which:

Fig. 1 is a diagrammatic fragmentary side elevation of a railway car with a waste disposal unit and control combination with the valve of the present invention installed therein, part of the car being shown in section for clearness in illustration;

Fig. 2 is an enlarged side elevation of the valve illustrated in Fig. 1;

Fig. 3 is a vertical sectional view taken on the lines 3—3 of Fig. 2;

Fig. 4 is a horizontal sectional view of the valve in open condition and is taken on line 4—4 of

2

Fig. 2, part thereof shown in plan for clearness in illustration;

Fig. 5 is a sectional view taken on the line 5—5 of Fig. 4;

Fig. 6 is a view similar to Fig. 5 with the air inlet lines omitted for clearness in illustration;

Fig. 7 is a sectional view similar to Fig. 4 but showing the valve in closed condition;

Fig. 8 is a fragmentary end elevation of the underside of the railway car showing the control mechanism for the valve;

Fig. 9 is a diagrammatic illustration of the valve, the air supply thereto, and the wiring diagram of the electrical control therefor.

15 Referring to the drawings, the invention is shown in connection with the railway passenger car, indicated generally at 1, and having the usual wheels 2 to the axle 3 of one pair of which is connected the usual generator 4 by means of

10 a belt 5. In the car shown for purposes of illustration the washroom 6 is shown as having the usual washbowl 7 and toilet 8, the drains of which lead to a down spout. If desired, in cars such as sleeping cars having roomettes and the like, the washroom and toilet facilities of a number of individual rooms may be connected to a common lead which in turn is connected to a single down spout.

15 In many cars, the down spout is open at all times for discharging along the trackway. In others it is connected to a large accumulating tank which is sealed during normal operation. Such accumulating tanks are arranged to be opened by an attendant and connected to sewage disposal systems in the larger stations where such disposal systems are provided. Thus they are drained only while the car is stopped. The equipment thus far described is well-known in the art and is such as is customarily provided on railway passenger cars.

20 In the present illustration, however, the down spout, instead of being open at all times or connected to an accumulating tank, is connected to the valve of the present invention.

25 30 35 In the present illustration, however, the down spout, instead of being open at all times or connected to an accumulating tank, is connected to the valve of the present invention.

40 45 50 As better illustrated in Figs. 2 and 3, the floor 9 of the car is provided with a passage 10 which is aligned with a collar 11 disposed on the underside of the floor. In existing cars, the collar is one adapted for connection to the down spout. In the present invention instead of the open down spout or the large accumulating tanks which can be opened only when the car is stopped, by an attendant outside of the car, a suitable accumulating sleeve 12 of much less capacity than the prior accumulating tanks is

connected to the lower end of the collar 11 in co-axial and depending relation thereto. At the lower end of the sleeve 12 the valve of the present invention is connected in co-axial and sealed relation thereto. The valve comprises a length of tube 13 which is preferably of resilient rubber and of substantially the same internal diameter as the sleeve 12. To the lower end of the tube 13 is connected a sleeve 14 which extends upwardly from the discharge end of the tube 13 in surrounding and shielding relation to the tube 13. The sleeve 12 is surrounded by suitable insulation 15 which in turn is encased in a rigid sleeve 17. The sleeve 17 is connected to the floor 9 or collar 11 and extends in surrounding co-axial relation to the sleeve 12 and to an upper end portion of the tube 13. Connected between the lower end of the sleeve 17 and the upper end of the sleeve 14 is an elongated housing 18 having aligned openings 19 and 20 in its top and bottom walls respectively, the openings 19 and 20 lying within the peripheral limits of the sleeves 14 and 17 and being of such shape as to accommodate the tube 13 in its normal undistorted generally cylindrical shape. By this arrangement, the passage from the inlet of the collar 11 through the tube 13 and sleeve 14 is of uniform size and unobstructed in any manner. An overflow and vent pipe 21 is provided near the top of the collar 11 and leads from the interior thereof to the outside atmosphere.

It is apparent that with the arrangement described, any material passing into the collar 11 can pass freely downwardly through the sleeve 12 and tube 13 and be discharged from the lower end of the tube 13 to the outside.

In order to open and close the passage through the tube 13 without introducing any obstructing valve mechanism thereinto or into the collar 11 or sleeves 12 and 14, means are provided for compressing and collapsing the tube 13 transversely of its axis so as to completely close the passage therethrough. It is desirable also that the closure of the passage through the tube 13 in this manner be accomplished even though some rigid article should happen to be between the walls of the tube at the point of closure. To effect closure in such a manner, the means pressed against the tube, at least from one side, must be flexible and such that, while maintaining the collapsing pressure, it can conform to the exterior surface of the closed tube 13 even when the outer surface of the tube is distorted to an irregular contour by being pressed into closing position about a rigid article disposed in the tube at the point of closure. For this purpose, the closure means illustrated has been found satisfactory.

Referring to Figs. 4 through 7, this means comprises a pair of inflatable tubes 22 arranged in the housing 18 at opposite sides of the tube 13 and preferably extending parallel to each other in a direction transversely of the axis of the tube 13. Each of the tubes 22 is of sufficient length to extend, lengthwise of the housing 18, beyond the tube 13 when the tube 13 is compressed to closed position as illustrated in Fig. 7. The tubes 22 are preferably resilient rubber laminated with fabric reinforcing and restraining strands and lie between the side walls of the housing 18 and the adjacent walls of the tube 13. The tubes 22 are closed at both ends by suitable closure caps 23. Connected through the cap 23 at one end of each tube is a flexible hose 24 which, in turn, is connected to a suit-

able pipe 25 which leads to the outside of the housing 18. The pipe 25 is connected to the usual compressed air line or source of the car, as is hereinafter described.

Adjacent ends of the tubes 22 are provided with rigid arms 26 which extend transversely of the housing 18 and are pivotally connected together by suitable upright pivot rods 27. The usual cotter pins 28 or other suitable means are provided for holding the arms 26 in proper position lengthwise of the rods 27. The rods 27 preferably are positioned midway between the adjacent ends of the tubes 22. Each of the rods 27 is provided with eyes 29 at its opposite ends. In order to floatingly suspend the tubes in the proper position in the housing 18, each eye 19 of each bolt 27 is connected to the ends of an associated pair of springs 30. The opposite ends of each pair of springs are connected to opposite side walls, respectively, of the housing 18 inwardly, lengthwise of the housing, from their associated rod 27. Thus, the springs normally support the tubes 22 within the housing for resilient floating movement and normally urge the rods 27 toward each other lengthwise of the housing so as to buckle the tubes 22 in a manner to cause the ends to move concurrently inwardly toward each other both transversely and longitudinally of the housing 18. This movement of the tubes results in the space defined between the tubes being relatively wide in proportion to its length. Normally, the springs hold the tubes in the position illustrated in Fig. 4 in which the tube 13 is fully open and defines an unobstructed passage from the collar 11 to the discharge end of the unit. Upon the introduction of air under pressure through the pipe 25, the tubes 22 are inflated and, since they are confined outwardly by the walls of the housing 18, press inwardly against the tubes 13 and, while adjusting themselves to its outer contour, apply sufficient force to collapse and close fully the tube 13, as illustrated in Fig. 7. Since both tubes 22 have flexible surfaces, they adjust themselves to any irregularity caused by rigid articles being caught between the contacting innerwall surface of the tube 13 and press the resilient or flexible walls of the tube 13 into closing relation tightly about the article. Upon release of the air pressure in the line 25, the springs 30 return the tubes 22 to the position illustrated in Fig. 4 and the tube 13 thereupon resumes its normal shape transversely. Such railway cars are normally provided with a source of air under pressure and suitable pipe lines for carrying it from one end of the car to the other. This air pressure, however, is several times that which is required for operation of the tubes 22. Accordingly, air from the usual main line, indicated at 32 in Fig. 9, is lead through a reducer 33 to an electromagnetic valve 34, the outlet end of which is connected to the pipe 25. The valve 34 is provided with a discharge or exhaust line 35 for exhausting the air to the outside atmosphere. It is necessary in a device of the character described that the tube 13 remain closed at all times while the train is in station areas and while it is approaching or leaving the station. Usually the speed of the train, when approaching or leaving a station, is quite moderate and the higher speeds are not reached until the train is a considerable distance therefrom. Accordingly, the present unit is arranged so that the tube 13 is closed at all times while the car is stopped or moving at relatively slow speeds and is opened only when the car reaches a prede-

terminated relatively high speed. For this purpose, the valve 34 is normally open so as to admit air under pressure through the line or pipe 25, thereby expanding the tubes 22 and closing the tube 13, and means are provided to operate the valve 34 in response to the speed of the railway car so as to stop the admission of air to the line 25 and connect the line 25 to the exhaust line 35, thereby releasing the air from the tubes 22 and permitting the springs to withdraw them and allow the tube 13 to open fully.

A suitable control mechanism for this purpose is illustrated in Figs. 8 and 9. Since the generator 4 of the car is driven in direct response to the rotational speed of the axle 3, a mechanism timed in response to the rotary speed of the generator will give a response directly proportional to the speed of the car. Accordingly, the generator is provided with an extension shaft 40 which is fixedly secured in co-axial relation to a sleeve 41. The sleeve 41 is rotatably mounted in a suitable bearing bracket 42. Mounted on the sleeve 41 is a fly ball governor and having arms 43 pivoted to a collar 44 which is rigidly secured to the sleeve 41. The inner ends of the arms 43 are connected to a suitable slide 45 in the sleeve 41. The slide 45 is moved longitudinally of the sleeve 41 in a direction away from the generator as the arms 43 swing relatively apart and is moved toward the generator as the arms approach each other under the influence of a return spring 46. Telescopically mounted in the end of the sleeve 41 and rotatable relative thereto is a cam rod 47. At its opposite end, the cam rod 47 is mounted a suitable bearing 48 and is urged toward the generator to a retracted position by means of a compression spring 49 which is interposed between the bearing of the bracket 48 and a suitable collar 50 secured on the rod 47. The end of the rod 47 and the bearing of the bracket 48 are preferably square, out-of-round, or suitably keyed so as to prevent rotation of the rod 47 in its bearing. Interposed between the slide 45 and the opposite end of the rod 47 is a suitable bearing ball 51 for transmitting the movement of the slide 45 to the rod 47 without imparting any rotary motion to the latter.

Carried on and movable with the rod 47 is a cam 52 for operating electric switches for controlling the operation of the valve 34. A suitable housing 53 is provided and encloses and protects the cam portion of the rod 47 and the cam 52. Mounted in the housing 53 are a plurality of normally closed limit switches, indicated at 54, 55, 56 and 57 respectively. Each of the switches is provided with the usual external lever 58. The switches are preferably arranged in a row in a position such that as the rod 47 is moved to the right in Fig. 8, the cam engages successively and operates the operating levers 58 of the switches 54 through 57 sequentially. Thus, the switches are operated in response to a predetermined relation to the rotational speed of the governor and therefore in response to a predetermined speed of the vehicle.

Each of the switches 54 through 57 is normally closed and is opened when its lever is engaged and operated by the cam as the cam moves to the right in Fig. 8. The switches are preferably of the so-called "microswitch" type and the operating lever is spring returned to normal position when they are released by the cam 52. Each one of the switches has one of its terminals connected to a common conductor 58 which in turn is connected to one terminal of the operating coil 59 of the valve 34. The other terminal of the coil 75

59 is connected by means of a conductor 60 to one side of the usual 32-volt direct current power line commonly provided on railway cars. The opposite terminal of each of the switches 54 through 57 is arranged to be connected selectively to the opposite side of the 32-volt power line, for completing a circuit through the coil 59 while a selected one of the switches is closed and to break the circuit when the selected switch is open. For this purpose, a plurality of contacts 62 through 65 are provided and are connected respectively to the said opposite terminals of the switches 54 through 57. A movable contact arm 66 is connected to the side of the 32-volt power line opposite that from which the coil 59 is connected. The movable contact arm 66 is so arranged that it can be swung to different positions to connect the switches selectively in the circuit and disconnect all except the selected one from the circuit. The movable contact arm and the contacts 62 through 65 are mounted on a suitable panel indicated at 67 which may be located at any convenient location in the railway car. By properly spacing the switches in relation to the movement of the rod 47, the switches can be made to open each at a progressively higher speed, beginning with the switch 54. Consequently by moving the arm 66 to connect the desired switch in the circuit, the coil 59 is energized only from the selected one and when that one is opened at its preselected speed, the coil is deenergized.

In general, it is desirable that the switches open at 40, 45, 50, and 55 miles an hour, respectively, beginning with the switch 54, as these speeds are usually not attained until the train is a considerable distance from the station. For example, assuming that the arm 66 has been moved to the contact 64 and the train speed is progressively increasing, the switch 54 is opened first followed by switch 55. But, since switches 54 and 55 are disconnected from the circuit, they have no operative effect, the switch 56 maintaining the circuit. When the train has reached a speed of 50 miles an hour, however, the switch 56 is opened thereby disconnecting the coil 59 from the circuit and releasing the air from the pipe 25 so that the tubes 22 are deflated and the tube 13 is opened. This condition obtains for this position of the arm 66 so long as the speed of the train is 50 miles an hour or greater. If the speed of the train decreases below 50 miles an hour, the cam 52 releases the switch 56 and it assumes its normally closed condition thereby energizing the coil 59 and re-admitting air to the tubes 22 and thereby closing the tube 13.

55 It is apparent from the foregoing description that the present valve and control mechanism makes possible the automatic discharge of waste only at preselected speeds of the train and eliminates the necessity for large and expensive accumulating tanks and the connection and disconnection of the same to local sewage facilities while the car is in the station. It also eliminates the inconvenience to passengers occasioned by the locking of the toilets while the train is in station areas.

While, for purposes of illustration, I have described my invention in connection with waste disposal units for railway vehicles, it is apparent that the valve is useful for other purposes wherein it is necessary to provide an unrestricted flow through a conduit while at the same time providing for the opening and closing thereof.

Having thus described my invention, I claim:

1. A flow control device comprising a flexible

wall tube collapsible transversely of its axis, a rigid confining housing for the tube and having a wall spaced laterally therefrom, a flexible inflatable tube interposed between the wall and the collapsible tube and having its axis in a plane lying at an abrupt angle to the axis of the collapsible tube and at least one end of the inflatable tube being secured in the housing for floating movement relative to the housing and to the collapsible tube in a direction generally endwise of the flexible inflatable tube.

2. A flow control device comprising a flexible wall tube collapsible transversely of its axis, a rigid confining housing having walls spaced at opposite sides of the tube, flexible inflatable tubes interposed between opposite sides of the collapsible tube and said walls, respectively, and positioned with their axes in a plane defining an abrupt angle with the axis of the collapsible tube, said walls constraining the inflatable tubes in a position in which, when inflated, they press against the opposite sides of the collapsible tube and collapse it, means to connect one end of the collapsible tube to a source of flowable material, means independent of the first means and uncommunicated therewith and adapted to connect the inflatable tubes to a source of fluid pressure and to disconnect them therefrom selectively, one end of each inflatable tube being mounted in the housing for movement relative thereto in a direction generally endwise of the inflatable tubes, and spring means operatively interconnecting the housing and said one end of each of the inflatable tubes and yieldably urging said ends of the inflatable tubes toward the opposite ends thereof, respectively.

3. A flow control device comprising a flexible wall tube collapsible transversely of its axis, a rigid confining housing having walls spaced at opposite sides of the tube, flexible inflatable tubes interposed between the collapsible tube and said walls, respectively, and positioned opposite to each other with their axes in a plane defining an abrupt angle with the axis of the collapsible tube, said walls constraining the inflatable tubes in a position in which, when inflated, they press against the opposite sides of the collapsible tube and collapse it, means to connect one end of the first tube to a source of flowable material, means independent of the first means and uncommunicated therewith, adapted to connect the inflatable

tubes to a source of fluid pressure and to disconnect them therefrom, selectively, at least one end of each of said inflatable tubes being mounted in the housing for movement relative thereto and to the collapsible tube in a direction generally endwise of the inflatable tubes.

4. A flow control device comprising a flexible wall tube collapsible transversely of its axis, a rigid confining housing having walls spaced at opposite sides of the tube, flexible inflatable tubes interposed between the collapsible tube and said walls, respectively, and positioned opposite to each other with their axes in a plane defining an abrupt angle with the axis of the collapsible tube, said walls constraining the inflatable tubes in a position in which, when inflated, they press against the opposite sides of the collapsible tube and collapse it, means to connect one end of the first tube to a source of flowable material, means independent of the first means and uncommunicated therewith, adapted to connect the inflatable tubes to a source of fluid pressure and to disconnect them therefrom, selectively, and spring means operatively connected to the inflatable tubes and operative to yieldably urge the inflatable tubes out of collapsible relation to the collapsible tube as the inflatable tubes are deflated.
